[57] CLAIM

The ornamental design for an organ console, substantially as shown and described.

DESCRIPTION

FIG. 1 is a front, top and right side perspective view of the organ console showing my new design;

FIG. 2 is a front elevational view; and

FIG. 3 is a left side elevational view.

The back of the organ console is plain, the fabric covering of the lower front board is continuous throughout the boundaries thereof and the spaces between the music desk mesh work are open.
